CLAIM

The ornamental design for a "food and beverage service tray", as shown and described.

DESCRIPTION

FIG. 1 is a front perspective view of a food and beverage service tray showing our new design;

FIG. 2 is a left side elevational view thereof;

FIG. 3 is a front elevational view thereof;

FIG. 4 is a rear elevational view thereof;

FIG. 5 is a right side elevational view thereof, the left side elevational view being a mirror image thereof; and,

FIG. 6 is a bottom plan view thereof.

The broken lines disclosed on FIGS. 1, 2 and 4 represent fold lines.
